UNITED STATES PATENT OFFICE.

RALPH W. RENTON, OF HAVERHILL, MASSACHUSETTS.

CARD-INDEX HOLDER.

Application filed June 26, 1925. Serial No. 39,653.

This invention relates to certain improvements in card index holders of the type on which the cards are detachably connected at one edge to a frame or flat support and lie 5 nearly flat in overlapping relation, so that the title, or other indicating mark on each card, will be exposed.

In holders of this nature, it is desirable to provide means whereby the cards may be 10 readily removed and replaced, and may be so mounted that they may be slid to different positions in the frame to permit the insertion of new cards and may at all times be held in properly spaced relation. It is 15 also desirable to employ in this connection cards of a type having a small wire secured thereto at one edge and having the ends project beyond the ends of the card, to provide a means for pivotally connecting the 20 card to the holder.

The objects of my invention are to provide a card holding means having the above described characteristics, which is of simple construction and is adapted to permit 25 the ready insertion and removal of cards of the character above referred to.

I accomplish these objects by providing a series of holders, each of which consists of a narrow strip of metal adapted to be slidably mounted in the guides of the card support, and is provided with a slotted socket 30 for the reception of the projecting wires of the cards which permits the same to be readily inserted.

For a more detailed description of a preferred embodiment of my invention, reference is made to the accompanying drawing in which:—

Fig. 1 is a plan view of an index card support or slide provided with card-holding means embodying my invention.

Fig. 2 is an end view thereof.

Fig. 3 is a detail view of the card-holding means which I employ, on an enlarged scale.

Fig. 4 is a detail view of a card fitted with the attaching means which I employ.

Fig. 5 is a sectional view, at line 5—5 of Fig. 4, on an enlarged scale.

Fig. 6 is a detail edge view of the card-holding means.

Fig. 7 is a sectional view of the frame at line 7—7 of Fig. 1.

Fig. 8 is a detail perspective view of a holder bar which I employ and

Figs. 9 and 10 are detail sectional views 55 and Fig. 11 is a perspective view, of one end portion thereof.

As shown in the drawing the main frame for supporting the cards is similar to that commonly employed in like devices, and comprises a flat support, or slide 10 having guide-way grooves 11 at its edges which open towards each other. A series of cards 12 are provided, each of which is fitted with a small resilient wire 13 at its upper end edge, the diameter of the wire being preferably approximately the same as, or but slightly greater than the thickness of the card and being secured thereto by a thin metal clip, or tab 14, of cloth or paper, which extends over the wire and is adhesively connected to each side of the card, as indicated in Fig. 5. Each wire extends continuously from end to end of its card and projects beyond the ends of the card to 75 form trunnions. Other means of attaching the wire than that indicated might be employed, for example, if the card is used in double form, as is frequently the case, it may be doubled about the wire, and independent means to secure it in place may be employed. The arrangement shown is however considered preferable, as the card may be inserted in an ordinary typewriting machine so that the matter to be written thereon may be typed on either side.

I further provide a holder for each card, which consists of a resilient metal strip 15 of a width corresponding to the width of the space which it is desired to separate the top edges of adjacent cards and of a length nearly equal to the distance between the bottoms of the guide grooves 11, the end portions of the strips are bent outwardly at right angles to form end guide faces 16, and then reversely, or towards each other to form top guide faces 17, the distance between which and the back side of the strip is slightly less than the width of the guide grooves, so that, when the end portions of the strip are placed in the grooves 11 it will be free to slide therein. The extreme end portions 18 of the strip are also bent inwardly at right angles, so that their end edges engage the strip portions underneath, and each end portion 18 is provided with a notch or slot 20, in the middle thereof, which opens to its end edge, so that the

notch is closed by the strip portion with which its end abuts, thereby providing sockets adapted to receive the projecting end portions of the wire 13. The card is placed 5 in the holder by bending the wire 13 sufficiently to permit its end portion to be inserted in the sockets 20, so that the portions 16 and 18 of the holder strip form a bearing for the wire, as shown in Figs. 2, 3, 6 10 and 9.

The card, having been placed in position in a holder, may be readily inserted in the 15 guide grooves of the support 10 by bending the holder and wire sufficiently to permit insertion of the heads formed on the end of the holder by portions 16, 17 and 18 thereof. When thus inserted, the cards will be pivotally suspended in the support and may be slid to any position therein, as indicated in 20 Figs. 1, 2 and 7. As thus arranged, the edges of adjacent holders engage, thereby providing proper spacing of the cards. If it is desired to remove a card, either the 25 card may be removed from its holder, or both the card and holder may be removed together, as will be obvious. When separated from its holder, a card may be readily inserted in a typewriting machine. To permit ready insertion of the fingers between the 30 holders and the support in which they are held, when they are to be removed, a rib 22 is provided in the middle of the support which causes the holders to be sprung outwardly at their middle portions, as indicated on Fig. 2. Follower blocks 24 may 35 also be provided in the guide grooves to hold the edges of the holders in contact if desired.

By forming the sockets 20 so that they 40 open to the surface of the strip, the facility with which the cards may be placed in position in the holders is increased, as with this construction, the wire 13 of the card may be held against the surface of the holder and the trunnion portions thereof, may be slid into the socket 20 while thus held, the surface of the holder thus forming a 45 guide to direct the end of the wire into the same. When a card is in position in its 50 holder, the edge portion thereof bearing the wire will be directly on the holder, when the card is resting flat on the support, or it

may be lifted slightly therefrom, as shown in Fig. 10.

The strips of metal, from which the 55 holders are formed, may be cut from sheet metal, the end portion being bent, to form the guides, either before or after cutting, according to the method of manufacture adopted. The notches 20 will be formed in 60 the ends of the strips before the bending operations thereon are performed.

The holder strips may be used indefinitely, as they do not have to be renewed when 65 the cards are renewed, and, whether each card which is renewed is supplied with a new wire, or with one which has been previously employed, is a matter of expediency, depending on the specific form of attaching 70 means for the wire which is considered desirable to employ. It may, however, be readily applied by one of several methods.

Aside from the features of advantage of the construction above referred to, the construction has the further advantage in that 75 the cards will lie nearly flat when the support is in the horizontal position and may be readily turned over, so that they will lie flat in the opposite position. The construction presents advantages in this respect over 80 those constructions which require the doubled form of card.

I claim:

In a card index of the character described, a flat support having oppositely disposed 85 guide grooves, a series of card holders each comprising a flexible metal strip having its end portions bent transversely and then reversely with relation to the intermediate portions of the strip, to form guiding portions 90 adapted to be slidably fitted in said groove, and being extended into proximity with the surface of the strip at their ends and having notches thereon forming sockets which are closed by the strip, and a series 95 of cards each having a wire trunnion projecting from each end at its top edge adapted to be removably inserted in said sockets to provide a pivotal connection therewith.

In testimony whereof, I have signed my 100 name to this specification.

RALPH W. RENTON.
